(57) **CLAIM**

The ornamental design for a portable medical monitor connector, as shown and described.

DESCRIPTION

FIG. 1 is a front perspective view of a portable medical monitor connector showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Uniformly-sized broken lines illustrate features of the portable medical monitor connector that form no part of the claimed design. Long-short broken lines illustrate boundaries of the claim and form no part of the claimed design. The stippling represents a color contrast from the other claimed features, but not any particular color.
